(57) **CLAIM**

The ornamental design for a nozzle for vapor-phase epitaxial equipment, as shown and described.

DESCRIPTION

FIG. 1 is a perspective view of a nozzle for vapor-phase epitaxial equipment, showing my new design;

FIG. 2 is a left side elevational view thereof;

FIG. 3 is a front side elevational view thereof;

FIG. 4 is a right side elevational view thereof;

FIG. 5 is a top plan view thereof;

FIG. 6 is a bottom plan view thereof;

FIG. 7 is a section view taken on line A-A' of FIG. 4; and,

FIG. 8 is an enlarged fragmentary view framed by lines B-B' and B'-B' of FIG. 3.

1 Claim, 2 Drawing Sheets
